UNITED STATES PATENT OFFICE.

JAMES M. MACK, OF PHILADELPHIA, PENNSYLVANIA.

GUIDE-BAR FOR LINING UP THE CURVES OF STREET-SURFACES.

SPECIFICATION forming part of Letters Patent No. 404,491, dated June 4, 1889.

Application filed March 5, 1889. Serial No. 301,885. (No model.)

To all whom it may concern:

Be it known that I, JAMES M. MACK, a citizen of the United States, residing at Philadelphia, in the county of Philadelphia and 5 State of Pennsylvania, have invented certain new and useful Improvements in Guide-Bars for Lining Up the Curves of Street-Surfaces; and I do declare the following to be a full, clear, and exact description of the invention, 10 such as will enable others skilled in the art to which it appertains to make and use the same, reference being had to the accompanying drawings, and to the letters and figures of reference marked thereon, which form a part 15 of this specification.

My invention relates to devices for lining up and regulating the arch or curve of the bed of a street, and has for its object the provision of curved liners or gages which are 20 used in pairs, each extending from the curb to the center of the street, where they meet and are suitably jointed. As many of these pairs as are desired may be arranged at suitable distances apart along the street extending 25 from curb to curb, and gravel, sand, or other filling material is then thrown until it is as high as the top of the arched liners or gages, and then a straight-edge is run transversely across the street from curb to curb, 30 and the bed will be found to be accurately and evenly arched. These liners or gages are preferably made T shape in cross-section, with the stem of the T projecting downward, which gives them strength and allows the stem to be 35 sunk into the bed of the street. These devices may be used to get the curve of alleys and narrow streets in which the center is the lowest by simply turning them upside down or reversing the curves.

40 The accompanying drawings illustrate my invention.

Figure 1 is a longitudinal section of a road-bed, showing the devices in place. Fig. 2 is a side elevation of the liners or gages. Fig. 3 45 is a transverse section of a road-bed.

Similar letters of reference indicate corresponding parts in all the figures where they occur.

A represents the bed of the street, and A' A' 50 the curbs.

B B are the liners or gages, which are arched as shown, and laid in pairs, as shown, extend-

ing from curb to curb, meeting in the center of the street, and, if desired, provided with an overlapped joint B*, which unites them in 55 such a way as to preserve the curve of the two gages or liners.

B' B' are wings on the under side of the gages, which in cross-section are T-shaped, the wings forming the stem of the T. The wings 60 strengthen the gages and preserve their arched form. These gages or liners are set in pairs across the street-bed from curb to curb at suitable intervals, the street filled up, and a suitable straight-edge C, resting each end on a 65 liner, is drawn across the street. This will strike the filling material to the same level and curve as the liners or gages.

If it is desired to line an alley or small street with the center depressed, it is only necessary to turn the liners or gages over.

The liners or gages are preferably made of metal. They may be made in one piece instead of two, as shown.

After the bed is rounded up the liners or 75 gages are removed and the channels which they have made are filled up.

Having thus described my invention, what I claim, and desire to secure by Letters Patent, 80 is—

1. A removable arched liner or gage for regulating the curve or arch of a road-bed formed upon a curve or shape to which the bed is to be conformed and having a flat top whose upper surface is adapted to coincide 85 with the surface of the pavement, as set forth.

2. A removable arched liner or gage for regulating the curve or arch of a road-bed, consisting of a curved metallic piece T- 90 shaped in cross-section, the head of the T resting upon and its top face being level with the upper surface of the filling, as set forth.

3. The combination of a pair of removable arched liners or gages extending from curb to 95 curb and meeting in the center of the road-bed and having an offset-joint, as set forth.

In testimony whereof I affix my signature in presence of two witnesses.

JAMES M. MACK.
